[57] ABSTRACT

A circuit for sensing reception of carrier in an information transmission system which employs valid detection of a carrier including filtering, comparison, and time delay, to determine propriety of a carrier, by a logic arrangement for digital interrogation including a pair of counters under the control of a third counter. Each of the pair of counters is advanced by signals derived from the detection circuitry over a predetermined time frame set by the third counter, and the counter outputs decoded to a deactivation device in the event of improper carrier detection. In addition, a resettable counter monitors the transmission during information flow. Failure to reset, indicating improper carrier, also triggers deactivation.

DATA COMMUNICATION SYSTEM

This invention relates to transceiver units and more particularly to a time sharable circuit within the transceiver unit for indicating receipt and detection of a carrier signal.

In data communication systems and in facsimile transmission systems in particular, it is necessary that a transceiver unit, when acting in the transmit mode, be provided with an accurate indication that the receiver unit is ready to receive a signal. Prior systems have operated manually, with operator adjustment of speed selection and detection of valid transmission. In automatic units, it is a further necessity that the transceiver unit, when in a receive mode, be provided with a suitable means for indicating the speed of the transmission unit carriage so as to properly synchronize receipt of the data communicated with the speed of the receiver carriage. The form of data communication device envisioned within the concept of the present invention relates specifically to the type employing transmission of data signals over telephone lines. Within the framework, available bandwidth, noise, and other such limitations must be taken into account in designing a suitable and effective system.

In facsimile transceiver systems, operation is accomplished by scanning documents at a transmit station, developing an electrical signal representative of the contents of the document, and modulating the signal in a form suitable for transmission over standard telephone transmission lines. These signals are referred to as "baseband" signals. The preferred form of modulation of such baseband signals is frequency modulation at a low frequency in the audio range transmissible by ordinary telephone circuitry. This frequency is normally in the range of 1,500 to 2,500 Hz. During transmission, the frequency modulated signal is coupled into a standard telephone transmission line by means of an acoustic coupler or similar type device and removed from the transmission line by a complementary type device at the receiving station. By use of frequency modulated signals, acoustic couplers in conjunction with telephone line devices may be employed without any special electrical requirements at the interface. At the receiving station the frequency modulated signal is demodulated to provide an electrical signal that can operate a suitable printing device. In the satisfactory operation of such a system, it is necessary to provide some means of assuring that both transmit and receive functions can be performed. With regard to the present invention, two specific requirements are necessary. First, it is necessary that a transceiver unit when in the transmit mode be provided with a signal indicating that the receiver unit is ready to receive. Secondly, it is necessary that a transceiver unit when operating in the receive mode possess the capability of detecting a signal transmitted by the transmitter for indicating to the receiver the speed of document processing transmission. The receiver can respond to the transmitted signal for adjusting its own speed in order to synchronize receipt of the transmitted signal with the reproduction capacity of the receiver unit.

Document assurance in transceiver equipment is sometimes referred to as "handshaking." This operation is the interchange of signals between a receiving unit and a sending unit prior to transmission, and electronic processing of these signals to allow the sending

unit to begin transmission only when a "ready" receive machine is connected. This is accomplished by detecting the specific frequency and duration of the receive units' "ready tone." The sender listens for this ready tone only when it is ready to transmit, i.e., when it is successfully loaded an original document, a handset is in the coupler, and a connected unit is "off hook." At the time it is ready to listen the sender is transmitting an intermittent tone. Obviously, if any receive machine transmits a different frequency or short duration "ready tone" or which transmits a valid "ready tone" when the sending machine is not ready to send, the "handshaking" will not be accomplished and the sender will not begin transmission. Automatic speed selection is the ability of a receive machine to adjust its carriage speed to correspond to that of the transmitting machine. This is accomplished by detecting a speed identification signal from the sending machine during the early part of the transmission.

In an automatic telecommunication system, it is necessary to provide for recovering information from transmitted signals regarding the particular format of a transmission. The automatic system operation requires the sensing and detecting of various conditions provided by a carrier signal. Before a detected carrier signal is considered valid, it must have conformed to certain requirements of automatic operation. As part of the present invention, multiple speed transmission units are employed, and speed signal information is incorporated as part of the carrier transmission.

It is therefore the prime object of this invention to provide unique circuitry for interrogating carrier.

It is a further object of the invention to provide a digitally operable interrogation circuit which will provide an indication of a valid carrier transmission with respect to the speed information being transmitted.

In accordance with the foregoing objects, a circuit arrangement is provided in a transceiver unit which will operate, when in a receive mode, to provide digital interrogation of a transmitted carrier to detect transmission speed information. For this invention, this interrogation is employed to provide carrier detection during the period that speed information is being transmitted. To this end, a pair of counters are provided which operate under the control of a third counter. When the transceiver unit begins to operate in response to a detected carrier signal, the interrogation operation begins. A filter, voltage comparator and time delay circuit detect one of two information signals being transmitted. The two signals are used to advance the two counters during a time frame defined by the third counter. At the end of the time frame, either one or the other of the pair of counters will have achieved predetermined count. Decoding of the counter outputs determines the information desired. If both counters or neither counter have achieved such level, error is indicated. To provide carrier detection during transmission of video information, at any of two or more speed levels, an additional counter logic circuit is provided which is continually reset by the proper transmission signal. Failure to reset indicates loss of carrier or improper transmission.

The automatic transceiver units described herein are capable of operation in both transmit and receive modes. For purposes of explanation, both modes will be described in conjunction with one embodiment of an exemplary sequence, it being understood that it will

be within the skill of the art to vary the operative time sequences and still employ the same conceptual basis of operation.

For a unit operating unattended in the Send mode, documents are loaded and the telephone handset inserted into the coupler causing the first document to be loaded onto the drum. An incoming call is answered and the machine starts sending an interrupted tone, for example, 0.25 second ON, 0.25 second OFF, indicating it is in the Send mode and ready to transmit. During the OFF portion of the cycle it listens for a signal indicating a ready condition, of for example 1,500 Hz, from a receive machine. Once the Ready tone is detected, the machine will start and send information concerning the document. At the end of document transmission an appropriate signal will be transmitted and the sender unit will simultaneously go into the next feed cycle. At the end of the cycle, such signaling will be transmitted as before. Also, as done initially, if a signal indicating the unit is ready is not detected in a given time frame, the connection can be dropped.

In the Receive mode, the loading operation is as previously discussed. When an incoming call is answered, the machine will send a signal indicating a ready condition at a predetermined rate, for example a 3.5 second rate; that is, 1.5 seconds of 1,500 Hz sending tone and detect receipt of carrier the other 2.0 seconds. Once carrier is detected, the machine will start and operate until either carrier is no longer detected or the document scan/print carriage reaches its limit. At this point, the automatic document feed cycle will again start and a suitable signal of for example 1,100 Hz will be sent. At the end of the feed cycle, a signal indicating ready condition will again be repeatedly transmitted awaiting the next copy. If detection of carrier is not satisfied within a preset time thereafter, the connection will be dropped and the next call answered.

It is advantageous from a cost economy viewpoint that the transceiver unit employ common circuitry for both transmit and receive modes. The circuitry to be described herein thus performs a validity check of such ready signals received during the transmit mode as well as interrogating carrier for speed selection during receive mode.

The foregoing objects and brief description will become more apparent from the following more detailed description when taken in conjunction with the appended drawings wherein:

FIG. 1 is a generalized block diagram of a transceiver system such as is contemplated within the scope of the present invention;

FIG. 2 is a generalized logic circuit illustrating the relative function of the components;

FIG. 3 is a schematic illustration of the functional relationships of the components forming the transceiver circuit;

FIG. 4 is a circuit diagram of the components forming the transceiver circuit;

FIG. 5 is a logic diagram illustrating the manner wherein the transceiver circuit operates with the speed selection portion of the present invention.

Referring now to FIG. 1, a brief description of a system with which the invention finds particular utility is illustrated. Within the generalized framework of the present invention a suitable transceiver system is shown in FIG. 1 with a first unit located at remote position A and a second unit located at a further remote position

B. Each of the transceiver units as shown are identical, each capable of transmitting or receiving a signal in accordance with the desired operation. Since the units shown under A and B in FIG. 1 are intended to be identical for purposes of this description, like reference numerals will be used to refer to like components with only the reference numeral subscripts delineating the distinction between unit A and B. Thus, in FIG. 1, a control unit 10 is illustrated as interacting with a processing unit 12 which coacts in turn with a processing drum 14 through print unit 16 and scan unit 18. The control unit 10 is in turn coupled to appropriate transducers 20 and 22 which form part of an acoustic coupling unit 24. The acoustic coupling unit 24 transceives appropriate signals to a data handset 26 which may be of a conventional audio telephone line, which in turn transmits signals over a transmission line 28 to the desired remote unit.

In operation, assuming unit A transmitting and unit 20 B receiving, an appropriate control signal is entered into the control unit 10A and an initial signal such as an interrupted tone is transmitted through the transducer 20A, the handset 26A and the data transmission line 28 to the receiving unit. When the receiving unit 25 is ready to receive, it will send an appropriate signal to the transmitting unit. In a ready condition, the receiving unit B transmits a ready signal and is operative to receive information. Facsimile transceiver devices are described in further detail, for example, in the Saeger et al. U.S. Pat. No. 3,432,613, issued Mar. 11, 1969 and assigned to the assignee of the present invention.

As was discussed above the signal transmission is based upon a modulated signal. When a transceiver is operating in its send mode, the transceiver is transmitting an appropriate signal to the receiver unit. Such signal is designed as an interrupted tone, to have an on period and an off period. The transceiver sending unit operates during the off period to detect the presence or absence of a ready signal from the remote receiver. The ready signal received from the remote receiver is in the nature of an audio tone suitable for transmission over telephone lines. Thus, for example, a ready signal may consist of a 1,500 Hz tone which must be of such duration that it will equal or exceed any maximum expected noise duration, as well as exceeding the period of the interrupted tone from the receiver. The reference to noise indicates the noise which falls within the bandwidth of interest.

As was described above in either the send or receive mode the transceiver circuit of the present invention is designed to respond to signals received from the corresponding remote unit to perform a desired function. Referring now to FIG. 2 an input signal received by the local transceiver unit which may correspond either to a ready tone (T) or a speed select signal (R) is received by a demodulator 30 which effectively translates the received signal to a DC level proportional to the received frequency. The DC level is coupled from the demodulator 30 to the transceiver circuit 32 which performs verification of a remote receiver ready signal or partial speed verification based upon transmission from a remote sender unit. Complete speed verification is accomplished by the combination of circuits 32 and 40. Send or receive mode is triggered by means of an appropriate send or receive signal coupled along the line 34 to the circuit unit 32. In the send mode, a signal ap-

pears along the line 36 indicating verification of a receiver ready signal which in turn activates a suitable machine activation unit 38 for initiating the transmission of the send unit. Should the unit be in the receive mode, the incoming signals refer to speed select and are coupled to and effectively delayed through the appropriate speed drive logic 40 along the lines 42 and 44 which in turn activates a suitable drive unit 46 for carrying into effect the speed select in accordance with the control signals thus received.

The demodulator unit 30 includes a further output line 33 which provides a signal in response to detection by the demodulator 30 of any form of carrier signal. This is termed an unvalidated carrier signal. The speed drive logic 40 provides speed signals along output line 41 representing detection of either of two transmitted carriers having speed information transmitted during the initial phasing period. A carrier detect validation circuit 43 responds to both the unvalidated carrier signal and the speed drive signals for validating carrier detection to insure that a legitimate transmission is being received. After the initial phasing period, and during information transmission, a further counter logic circuit 37, driven by clock pulses along input line C responds to information signals appearing on lines 42 and 44 to present a validation condition to the carrier detect validation circuit 43 which, along with an unvalidated detected carrier signal appearing along line 33, responds to proper signal conditions on lines 42 and 44 to provide continuing carrier detect validation. The validation circuit 43 is coupled to the machine drive 47 and can provide a disconnect signal thereto as a result of improper carrier detect.

Referring now to FIG. 3, the transceiver circuit 32 is illustrated in greater detail. As shown, the input signal received from the demodulator unit 30 is coupled along a line 50 to an input filter 52. The output of the input filter 52 is coupled to a voltage window detector 54 having positive and negative voltage range limitations coupled into the terminals 56 and 58 respectively by means of appropriate valued reference sources. The output of voltage window detector 54 is coupled through a gate 62 which is coupled in turn to a selective discrimination circuit 64 which serves with two delay functions sufficient to distinguish a received ready signal or a speed select signal from spurious input noises within the same bandwidth. A logic input 66 coupled to the circuit 64 provides an indication to the circuit 64 as to which of the send or receive modes the transceiver circuit 32 is operating and therefore dictates which time delay is appropriate. The output of the voltage window detector 54 is further coupled to a speed detecting circuit 68. This circuit also includes delay to distinguish over noise. The circuit 68 is designed for detecting a second frequency level signal indicating that a different speed signal is being transmitted and thereby in conjunction with the logic delay and control circuitry energizes the alternate speed of the transceiver.

By way of simplifying design, the transceiver circuit 32 can be designed to accommodate the same frequency signal indicating receipt of a remote receiver's signal ready condition as would indicate one of the speed select signals from a remote transmitter. The receiver ready signal for the transceiver circuit operating in the send mode is also a voltage corresponding to a frequency level of 1,500 Hz. The present invention as

illustrated shows the use of two speed select signals. The first of these signals is represented by a voltage corresponding to a frequency of 1,500 Hz, the second of these signals is represented by a voltage corresponding to a frequency of 1,100 Hz. It should be apparent that additional speed controls can be provided by the use of additional voltage corresponding frequencies, limited only by the bandwidth of transmission line and other factors incident within the data communication system employed.

The demodulated DC signal appearing along the line 50 is applied to the input filter 52 for purposes of smoothing and eliminating any ripple or other transient component appearing along the line 50 after the demodulation. As noted above, the DC voltage appearing along the output line of the filter 52 will correspond directly to the frequency level appearing at the input of the demodulator unit. The voltage window detector 54 is designed to have an upper and lower voltage limit. When the DC signal emerging from the filter unit 52 falls within the band set up by the two reference potentials appearing along the lines 56 and 58, or thus falls within the window, the gating circuit 62 responds thereto and provides an appropriate signal level along the output from the gate 62 to the circuit 64. When the circuit 64 is in the send mode, the internal delay of the circuit 64 will prevent the appearance of an output signal until the prerequisite time period has passed during which the signal applied from the gate 62 to the circuit 64 continues. Loss of this signal at any time during the send mode will immediately reset the delay period of the circuit 64, thereby preventing initiation of a transmission. Thus, transmission will not be initiated without the requisite presence of a suitable time extended ready signal received from the remote receiving unit. Incidentally, any information signal not received for a sufficient duration will have a similar effect on operation.

The time delay of circuit 64 is set by means of an input supplied along the line 66. Receipt of a signal by the voltage window detector 54 which falls outside of the voltage window, either above or below, will result in either one or the other inputs to the gate 62 being effectively blocked. Thus, the unit 64 will not operate unless a properly received signal falls within the frame of the voltage window designed into the voltage window detector as received thereby.

When the local transceiver and the circuit 32 are operating in its receive mode condition, during the initial period of transmission, the demodulated input signal along the line 50 will include information relating to a characteristic of a remote transmission unit. Specifically, the signal appearing along the line 50 during this initial transmission includes a signal portion referred to as the phasing signal and provides speed selection information indicating the transmitter speed. The phasing signal is smoothed through the input filter 52 and applied to the voltage window detector 54. The two signals chosen for purposes of speed selection in this embodiment are a 1,500 Hz signal, and an 1,100 Hz signal. The DC level proportional to the 1,500 Hz signal, as described before, will pass through the voltage window detector, activate the gate 62 when within the window, and generate through the circuit 64 an appropriate output signal along the 1,500 line indicating that a 1,500 Hz signal has been received. Appropriate machine activation is then effected after a number of these 1,500

line outputs, through logic circuitry to be described in further detail below. Again, as before, the circuit 64 is provided with an indication of the operational mode by means of an appropriate signal applied along the line 66. Should the input signal represent the other speed selection frequency, that of the 1,100 Hz, the appropriate voltage applied to the voltage window detector will in this instance fall below the voltage window. In this case, the output line 70 of the voltage window detector 54 will be activated whereas the output line 72 of the voltage window detector 54 will not be activated. A circuit 68 responds to the activation along the line 70 to provide an appropriate output signal along the 1100 line indicating the particular frequency detected and the speed corresponding thereto. Again appropriate logic circuitry responds to a number of these 1,100 signals for activating the appropriate speed control, as will be described in further detail below.

Referring now to FIG. 4 a more detailed description of the circuit 32 is provided. Thus, in FIG. 4 the input filter 52 includes a filter configuration known as a Paynter filter which in this example is a low pass three pole filter having a corner frequency designed at 300 cycles. A Paynter filter has been chosen for this particular example because of its important excellent time domain response characteristics. Fast time domain response is necessary in order to follow the switching DC level associated with the phasing signal received when the unit is in its receive mode. The input signal on line 50 is smoothed by the filter to substantially attenuate any transient interference or ripple, and to present as steady a potential level as possible to the voltage window detector 54.

As shown in FIG. 4, the filter 52 includes an input resistor 520, a shunt capacitor 522, a set of series resistors 524 and 526 and a second shunt capacitor 528. The differential amplifier 530 receives the input from the filter along its first positive input terminal 532 and the output therefrom appears along the output line 534 and its feedback line to the second negative input terminal 536 and through a capacitor 538 to the junction point between the series resistors 524 and 526. The output of the filter unit, passing along line 60, is next coupled to the voltage window detector 54. The voltage window detector 54 includes a resistor string having resistances 540, 542 and 544 connected in series across a voltage supply provided by a first source +V1 and a second source -V1. The desired voltage range for the window is provided by adjusting the values of the resistances 540, 542, 544 such that the intermediate taps will result in the desired voltage points. These resistances may be fixed, as shown, or variable to permit fine adjustment of the window range. The voltage window detector 54 includes differential amplifiers 546 and 548, each having differential input terminals illustrated respectively as 550, 552, 554 and 556. Input terminal 550 is coupled to the junction of the resistors 540 and 542, input terminal 556 is coupled to the junctions between resistors 542 and 544, and the common connection between terminals 552 and 554 of the amplifiers 546 and 548 are commonly connected to the input line 60 of the voltage window detector 54. The operational amplifiers 546 and 548 are each powered by the power supply units +V1 and -V1 as illustrated. Ripple elimination capacitors 558 and 560, as indicated, couple the resistor string potential supplies +V1 and -V1 to ground. The output lines 70 and 72 appearing from

the voltage window detector 74 are coupled to the gating unit 62 which consists of first and second unilaterally conducting devices illustrated as the diodes 620 and 622. These diodes are coupled directly to the input lines 72 and 70 respectively. The output of the diodes is coupled along a line 624 to the discrimination circuit 64.

As illustrated, the discrimination circuit 64 includes a current limiting resistor 640 coupling the input signal from the gating unit 62 along the line 624. The send/receive mode signal line 66 is connected through a current limiting resistor 642 which is in turn connected to the base electrode of a transistor 644. Further biasing is supplied by a resistor 644 from a source of potential +V1 to the base of the transistor 644. The emitter electrode of the transistor 644 is shown as coupled to the source +V1. The collector electrode of the transistor 644 is connected through a resistance 648 to a common junction point 650. The resistance 648 acting with respect to the potential source +V1 forms an RC circuit, as will be explained in further detail below, along with capacitor 652 which is coupled between a source -V1 and the junction point 650. A further resistor 654 forms a second RC circuit between a source of potential +V1 in conjunction with the capacitor 652 to the second source of potential -V1. A unilateral conduction device, diode 655, is coupled between a source of potential +V2 and the common junction point 650. The signal appearing at the junction point 650 is coupled to the base electrode of a further transistor 656. The emitter electrode of transistor 656 is coupled through a current limiting resistance 658 from the potential source +V1. The collector electrode of transistor 656 is coupled through a current limiting resistor 660 to a suitable source of potential -V1. The emitter electrode of the transistor 656 is coupled through a diode 662 to the base electrode of the transistor 664, with a biasing resistor 666 coupling the base electrode of the transistor 664 to ground potential. The transistor 664 at its collector electrode is coupled to a potential source +V2 acting through a current limiting resistor 668, while its emitter electrode is coupled directly to ground. The output line 670 of the transistor 664 is taken from the collector electrode thereof and corresponds to the 1,500 signal output.

The speed detecting circuit 68 as shown includes an input resistor 680 coupled to the output line 70 of the voltage window detector 54. The resistor 680 couples the output appearing on line 70 to the base electrode of a transistor 682. The transistor 682 has its collector electrode coupled to a source +V1 through a current limiting resistor 684. The emitter electrode of the transistor 682 is coupled by means of a resistor junction consisting of series connected resistors 686 and 688 from a source -V1 to ground potential. A further capacitor unit 690 forms an RC circuit with the resistor 684 in a manner which will be described in further detail below. The junction of the capacitor 690 and resistor 684 is coupled through a diode 692 to the base electrode of a transistor 694. A biasing resistor 696 couples the base electrode of the transistor 694 to ground. The collector electrode of the transistor 694 is coupled through a current limiting resistor 698 to a source +V2. The emitter electrode of the transistor 694 is coupled to ground. The 1,100 output of the speed detecting circuit 68 is taken from the collector electrode of transis-

tor 694 along an output line designated by the reference 1100.

Describing briefly the operation of FIG. 4, a demodulated signal appearing at the line 50 passes through the three pole Paynter filter 52 and is smoothed by the combination of resistor and capacitor networks shown in a well known manner. The filtered voltage appearing at the line 60 is introduced to complementary inputs of the differential amplifier 546 and 548 which receives as reference voltage levels the voltage appearing at the respective junctions of the resistor string formed between the voltages +V1 and -V1. The operation of the differential amplifiers is such that a voltage appearing along the line 60 which falls between the window defined as the spread between the two reference voltage levels applied to the input terminal 550 and 556 of the differential amplifiers 546 and 548 will result in a positive output voltage from both amplifiers 546 and 548. A voltage falling above the window will result in a positive voltage at the output of differential amplifier 548 and a negative voltage at the output of differential amplifier 546, a voltage appearing below the window will result in a negative voltage output at the differential amplifier 548 and a positive voltage output at the differential amplifier 546. A voltage that appears within the window resulting in a positive output from differential amplifiers 546 and 548 along lines 72 and 70 respectively will block conduction of diodes 620 and 622 in the gating unit 62. As a result of blocking of the diodes 620 and 622, a high impedance path is provided at the beginning of the line 624. Meanwhile, the circuit 64 has received an indication along the input terminal 66 as to whether the unit is in a send or receive mode. For example, if the unit is in a send mode a logic signal, i.e., one, will have been applied to the terminal 66 which will have the effect of presenting an open circuit thereon. If the terminal 66 represents an open circuit, indicating the unit to be in a send mode, transistor 644 will be biased to an off condition, thereby representing a high impedance path through the resistance 648. Thus the only impedance path presented for the junction point 650 will be through the resistance 654. The resistance 654 is provided with relatively large value relative to the resistance 648. As a result, the capacitor 652 will begin to charge at a rate such that it will not reach an appropriate triggering level for a period of time determined by the maximum amount of noise forecast for the system. In the present example, a time delay of 100 milliseconds is assumed. The transistor stage 656 is arranged as an emitter follower circuit, and provides isolation of the output stage from the charging circuit. At the end of the time delay period the voltage of the junction point will have reached a sufficient level to cut off the transistor 656 and in turn apply a positive voltage to the base electrode of the transistor 664, and thus provide output signal along the line 670 indicating the valid presence of a 1,500 Hz signal.

In the speed select mode, and assuming receipt of a voltage level corresponding to a 1,500 Hz input, indicating one of the two speed levels to be selected, a logical 0 is applied to the terminal 66 which will have the effect of grounding that terminal. As a result, transistor 644 will be rendered in an on condition, and the charge path defined for capacitor 652 will be the RC circuit including capacitor 652 and the parallel connection resistors 648 and 654. The resistor 648 will have a lower design impedance than the resistor 654. As a result, the

voltage junction point 650 will reach the triggering level after a much shorter delay time. This time delay is designed to insure against detection of a non-valid phasing pulse, such as short noise pulses, transients or the like. The time delay serves the same function for speed selectors it does for ready detection. The reason for the shorter time delay is based upon the nature of the speed select signal. The speed select signal is transmitted as pulses that may be as short as 12 milliseconds while the ready signal may be several seconds long. Further time delay is accomplished by the select circuitry. In both of the foregoing described situations the diode 655 clamps the junction point 650 to a lower potential +V2 to prevent the capacitor from continuing to charge up to a maximum voltage level which may have the effect of destroying the transistor 656.

If the output voltage of the filter 52 falls above or below the window, the capacitor charging circuit will not be rendered effective, since a low impedance path will be formed along the input line 624 through one of the diodes 620 or 622. If a voltage corresponding to the 1,100 Hz input has been received by the filter unit 52 and applied along the line 60, it will result in a signal applied along the input resistor 680 to the circuit 68 which will have the effect of turning off the transistor 682 which is held in a normally on condition. With the transistor 682 turned off, an RC charging path is provided composed of capacitor 690 and resistor 684 between the sources of potential +V1 and -V1. Again, the time delay involved in this charging circuit can take into effect an average condition of potential noise limitations. Upon reaching the proper charging level at the junction of capacitor 690 and resistor 684, a signal is passed through the diode 692 to the base electrode of transistor 694, rendering same conductive and allowing an output pulse to appear along the 1100 line.

Referring now to FIG. 5 there is illustrated that portion of the logic circuitry which is employed for providing the appropriate speed select in accordance with signal representations received from the circuit illustrated in FIG. 4.

As shown in FIG. 5, for purposes of illustration a 15 second timing cycle is employed. Counter units T1, T2 and T3 are employed simultaneously to perform the speed select function. Each of the counters includes a count input terminal C, a reset input terminal R and output terminals 0 from which the state of the counter may be derived. As explained in detail above, the transceiver unit is in its receive mode during the speed select operation. During the initial information transmission phasing period, detection of a carrier indicating the presence of an incoming signal and absence of any fault conditions is supplied by means of a logical 1 along the terminal 700. In the receive mode, this signal may be derived from output line 33 of demodulator 30. This logic 1 is converted to a logical 0 through the inverter unit 702 and applied to a first input of gate 704. Unless otherwise indicated, each of the gates referred to in FIG. 5 is a logical NAND gate. A logical 0 at the input of gate 704 will result in a logical 1 at the output of gate 704 being coupled to an input of gate 706. The other input of gate 706 during this period is a logical 1. The output of gate 706 therefore is a logical 0, and coupled in turn to the reset input of counter T1. The counter T1 operates to reset upon receipt at its reset terminal of a logical 1.

System timing is controlled by a standard 60 Hz waveform along input line 708 to a clock divider 710. The clock device 710 divides the input frequency to a two cycle per second rate. Assuming no fault condition existing on fault input line 712, a logical 1 appears along line 712 which is coupled in turn with the output of the clock divider 710 to a gate 714, the third input of which also receives a logical 1 during this time span. The third input to the gate 714 is derived from the output of gate 716, which is in turn receiving an input from a decoding unit 718.

The function of the decoding unit is to determine the elapse of a $7\frac{1}{2}$ second period, which at a two cycle per second clock input at the C input of counter T1 will result in a count of 15 at the elapse of $7\frac{1}{2}$ seconds. The decoder 718 is non-inverting and responds, in well known manner, to a count of 15 in the counter T1 for providing a logical 1, coupled in turn to the gate 716. Prior to achieving a count of 15 in a counter T1, a logical 1 appears at the output of gate 716 and is coupled to the input of the gate 714 as described above and also to the input of the gates 704, 719, 720 and 722.

The output of each of the counters T2 and T3 have coupled thereto decoding units 724 and 726 which act in a complementary manner with respect to decoding unit 718, achievement of a predetermined count producing a logical 0. That is to say, a count of 15 appearing in either counter unit T2 or T3 will result in a change of state of the decoder unit 724 or 726, producing a logical 0. In the absence of such count, a logical 1 appears at the output of each of the decoder units 724 and 726. Inverter unit 728 inverts the logical 1 at the output of decoder 726 to a logical 0 and feeds it back to the first input of the NAND gating unit 730. In a like manner, inverter unit 742 inverts its respective decoder 724 output and feeds it back to a first input of gate 720.

The logical 0 output of inverter unit 702 is coupled to further inverter unit 732 and the logical 1 applied to the first input of the gate 719, and the gate 722. During this time period, however, the pulse input signals received on input terminals 727 and 736, corresponding to the 1,500 and 1,100 cycle speed signals respectively, are coupled to the gates 719 and 722 as logical 0's. Since logical 1's are applied along the respective input terminals 727 and 736 during the initial period prior to energization of either a 1500 or 1100 line, the gated pulse outputs of gates 719 and 722 are fed to inputs of T2 and T3 respectively, and each of the counters begin counting. When either the counter unit T2 or T3 reaches a count of 15, a change in logical state from 1 to 0 occurs at the output of the decoder unit 724 or 726. Upon reaching a count of 15 in either counter T2 and T3, the output of the decoder unit 724 or 726 goes from a logical 1 to a logical 0, and is then converted to a logical 1 through inverter unit 742 or 728. The signal is fed back to the input of gates 720 and 730, thereby converting the logical signal at the output of gate 720 or 730 from 1 to a 0 respectively. As a result gate 719 or gate 722 is disabled thereby effectively uncoupling the source of pulses from terminals 727 or 736 from either of the counters T2 or T3. Thus a count of 15 is held in either counter upon a count of 15 being achieved therein.

At the end of the $7\frac{1}{2}$ seconds, the decoding unit 718 decodes a count of 15 achieved in counter T1 and causes the logical output of the decoder 718 to go from

0 to 1 thereby effectively changing the output of NAND gate 716 from a 1 to a 0. The 0 signal when applied to the input of gate 714 uncouples the counter T1 from the source of clock pulses 710. As a result of the change of the state of NAND gate 716, all three counters are effectively disabled in a like manner. If, T3 had counted 15 1100 pulses during this counting period, this would have meant the presence of an input at the 1100 terminal 736 and the resultant logical 1 signal appearing at the output line 744 would energize a corresponding control device such as a relay converting the speed of the receiving carriage to the appropriate level corresponding to the transmission. The operation is designed such that a logical 0 appearing along the output line 744 would have allowed the unit to run in its alternate speed condition. A simple relay switching control (not shown) can be employed to activate one or the other of the speed conditions, depending on the appearance or non-appearance of a signal on the line 744.

The phasing signal received from a sending transceiver unit operates in accordance with this example to send three 1,500 or 1,100 pulses every second. As a result, 21 pulses can appear at either the input to the counter T2 or the counter T3 in the $7\frac{1}{2}$ second time frame that the counter T1 is operative. Therefore, either T2 or T3 should reach a count of 15 during the $7\frac{1}{2}$ second time frame. The foregoing characteristic can be employed to validate a detected signal, since the occurrence of both or neither counter reaching a count of 15 would be indication of an operative error. To detect and prevent such occurrence, the carrier detect validation unit 43 is provided with a gating unit 746 formed by a first NAND gate 748 and a second NAND gate 750, each having their outputs coupled to the input of NAND gate 752. The first NAND gate 748 has a first input responsive to the output of the inverter 742 and a second input responsive to the output of the decoder unit 726. The NAND gate 750 has a first input responsive to the output of the decoder unit 724 and a second input responsive to the output of the inverter unit 728. Since each decoder unit 724 and 726 is operative only upon counter unit T2 or T3 respectively reaching a count of 15, only one of the decoder outputs at the end of a sampling time frame will have achieved a state represented by a logical 0. The operation of NAND gates 748 and 750 clearly provides that if a 0 is present at the output of both decoder units 724 and 726, or if neither of the T2 or T3 counter units have achieved a state of 15 and both outputs of the decoder units 724 and 726 are at a 1 state, outputs will be provided in the form of logical 1's to the respective inputs of the NAND gate 752. A further input of the NAND gate 752 is responsive to an inverter unit 754 which in turn receives its input from the NAND gate 716. In the event logical 1 signals are provided from the gating unit 746, the coincidence of logical 1's at the inputs of NAND gate 752 will result in a change of state at the output of the NAND gate 752 thereby placing a logical 0 at the input of a storage circuit 756 through an AND gate 753. The second input of gate 753 is normally at a logical 1 level as will be described further below. The output of the storage circuit as a result of a logical 0 input will cause a 0 condition to appear along the output line 758, thereby activating a machine shutdown (circuit not shown). The other input terminal 760 of the storage circuit 756 responds to an unvalidated car-

rier detect signal which may be derived during the receive mode by means of any form of appropriate detection circuitry, for example, as from the demodulator 30. The appearance of the carriage detect signal in the form of a logical 0 at the input terminal 760 causes the storage circuit to produce a logical 1 at the output 758, thereby allowing the machine to run again upon receipt of the next unvalidated carrier detection.

During transmission, either 1,500 or 1,100 pulses continue to appear along terminals 727 and 736. This feature is employed to advantage in providing continued validation of detected carrier by virtue of the counter logic circuit 37.

The counter logic circuit 37 includes first and second JK flip flops 762 and 764 interconnected in conventional manner as a two stage counter. The counter runs under the control of the 2 Hz clock signal provided by the clock divider 710. The counter logic circuit 37 includes an input gate 766 responsive to a series of input signals corresponding respectively to an initial unvalidated carrier received by the unit and indicating initiation of a receive cycle, provided from terminal 700, an 1,100 signal from terminal 736, and a 1,500 signal from terminal 727. The gate 766, which is an AND gate, acts in response to the presence of a signal on terminal 700, i.e., a logical 1, and the pulsing of either the 1,100 or 1,500 signals for providing a reset signal to the counter stages 762 and 764. The counter is advanced by the 2 Hz rate to a count of three, and if no reset signal is received prior to reaching a count of three, thus indicating absence of both 1,100 and 1,500 signals, a logical 0 is provided at the output of a NAND gate 768 indicating a false carrier. The output of NAND gate 768 will be at a logical 1 level for all conditions except when the counter stages reach a count of three. The logical 0 at the output of gate 768 is supplied to the input of an AND gate 753, producing a logical 0 at the input of storage circuit 756, thereby terminating machine operation as described above.

At the end of a legitimate transmission, the input terminal 763 responds to a 1 condition which sets a logic unit 765 such that the output line 767 of the logic unit 764 goes to a 0 condition, thereby producing a 1 logic condition at the output of gate 706 and inverter 769, as a result of which counter units T1, T2 and T3 are reset by the appearance of a 1 input at their R terminal. The logic unit 64 maintains this condition 1 momentarily and may consist of a monostable multivibrator or an automatically reset bistable circuit.

The logic circuit described in FIG. 5 can clearly include additional means and modes whereby detection of the various conditions necessary for the selecting and actuating of machine drives as well as other processing equipment in accordance with sequence signals received by either remote send or receive units can occur as desired. Thus, it would be within the skill of the art to provide additional inputs selecting or non-selecting various gates in response to types of fault conditions existing with this type of equipment. In addition logic signals can be received and decoded which would indicate whether the local or remote unit, in accordance with the operation, includes or does not include necessary complementary equipment for sending or receiving speed control signals or the receipt of ready control signals.

It is noted that although specific detailed circuit configurations for the various units such as the counters,

NAND gates, decoders and inverters, as disclosed in the logic circuitry of FIG. 5, have not been given, such arrangements are considered to be clearly within the skill of the art.

The foregoing description has thus described a novel apparatus for securing a successful carrier validation signal, along with a document assurance operation between remote units as well as providing for speed selection in a time sharable circuit. As is obvious to those skilled in the art, many modifications may be made in the disclosed apparatus without departing from the spirit of the present invention.

What is claimed is:

1. A digital interrogation system for validation of a transmission carrier at a receiver unit comprising means for detecting unvalidated carrier, a first circuit responsive to said detecting means for providing a first signal in response to first transmission characteristic of said carrier and a second signal in response to a second transmission characteristic of said carrier, and a logic circuit responsive to either said first signal or said second signal for providing an output signal, said logic circuit including a counter, means applying a clock signal to said counter, means applying a reset signal to said counter, said reset signal including said first and second signals, said first and second signals acting to reset said counter prior to said counter achieving a predetermined condition, and gating means responsive to said predetermined condition for providing said output signal indicating neither said first or second transmission characteristic.
2. A digital interrogation system for validation of a transmission carrier at a receiver unit comprising means for detecting unvalidated carrier, a first circuit responsive to said detecting means for providing a first signal in response to first transmission characteristic of said carrier and a second signal in response to a second transmission characteristic of said carrier, and a logic circuit responsive to either said first signal or said second signal for providing an output signal, said logic circuit including a first counter having a fixed duration counting period and responsive to said means for detecting unvalidated carrier, said first circuit detecting an initial portion of said carrier for providing said first and second signals in response to transmission information conditions, a second counter responsive to said first signal for initiating a count therein, a third counter responsive to said second signal for initiating a count therein, said second and third counters each having a predetermined maximum count condition, means responsive to termination of said fixed duration counting period for sampling said second and third counters, a further gating unit, gating means coupling the output of said second and third counters to said further gating unit, said further gating unit providing said output signal if neither or both of said second and third counters had achieved said predetermined maximum count condition during said fixed duration counting period, and means responsive to said output signal indicating transmission error.
3. A digital interrogation system for determining a transmission condition at a remote receiver unit, com-

prising means for detecting unvalidated transmission carrier, a first counter responsive to said detected carrier for initiating a fixed duration counting period, detecting means responsive to an initial portion of said transmission carrier for providing first and second signals corresponding to first and second transmission information conditions, a second counter responsive to said first signal for initiating a count therein, a third counter responsive to said second signal for initiating a count therein, said second and third counters each having a predetermined maximum count condition, means responsive to termination of said fixed duration counting period for sampling said second and third counters, a further gating unit, gating means coupling the output of said second and third counters to said further gating unit, said further gating unit providing an output signal if neither or both of said second and third counters had achieved said predetermined maximum count condition during said fixed duration counting period, a means responsive to said output signal indicating transmission error.

4. The combination of claim 3 further including first gating means coupled to said second counter, second gating means coupled to said third counter, said first and second gating means each responsive to the respective second and third counter conditions for disabling the respective counter if said respective counter achieves its predetermined maximum count condition during said fixed duration counting period.

5. An arrangement for validation of an input signal having either of a first or second characteristic comprising

first means for detecting said input signal,
second means responsive to said first means for providing a first output signal in response to detection of said first characteristic and a second output signal in response to detection of said second characteristic, third means responsive to said first or second output signals for producing a third output signal, said third means producing a fourth output signal in response to the absence of said first and second output signals within a predetermined period of time, and fourth means responsive to said first means and said third output signal of said third means for validating the input signal detected by said first means, said fourth means being further responsive to said fourth output signal for invalidating the input signal detected by said first means.

6. The combination of claim 5 wherein said third means includes a counter means applying a clock signal to said counter, means applying a reset signal to said counter, said reset signal including either of said first and second output signals, said first and second output

signals each acting to reset said counter prior to said counter achieving a predetermined condition by virtue of said clock signal, and gating means responsive to said counter achieving said predetermined condition for providing said fourth output signal.

7. The combination of claim 5 wherein said third means includes a first counter having a fixed duration counting period and responsive to said first means, said second means responsive to an initial portion of said input signal for providing said first and second output signals in response to said first and second characteristics, a second counter responsive to said first output signal for initiating a count therein, a third counter responsive to said second output signal for initiating a count therein, said second and third counters each having a predetermined maximum count condition, means responsive to termination of said fixed duration counting period for sampling said second and third counters, a further gating unit, gating means coupling the output of said second and third counters to said further gating unit, said further gating unit providing an output signal if neither or both of said second and third counters had achieved said predetermined maximum count condition during said fixed duration counting period for providing said fourth output signal, and means responsive to said fourth output signal indicating transmission error.

8. In a receiver for use in an information transmission system wherein prior to information transmission pulses of a first frequency are transmitted to identify a first information transmission condition and pulses of a second frequency are transmitted to identify a second information transmission condition,

means for detecting an incoming signal, said detecting means providing a first output signal when said incoming signal is at said first frequency and a second output signal when said incoming signal is at said second frequency,
a first counter incremented in response to said first output signal,
a second counter incremented in response to said second output signal,
a third counter responsive to a clock signal for defining a fixed time period and providing a third output signal indicating the elapse of said time period, and

means responsive to said third output signal for sampling said first and second counters to provide an error signal if neither or both said first and second counters have reached a predetermined count and to provide a carrier validation signal if only one of said first and second counters has reached said predetermined count.
